UNITED STATES PATENT OFFICE.

JOHN A. STAPLES, OF NEWBURGH, NEW YORK, ASSIGNOR TO STAPLES & HANFORD COMPANY, OF NEWBURGH, NEW YORK, A CORPORATION OF NEW JERSEY.

SPRINGWORK.

SPECIFICATION forming part of Letters Patent No. 783,596, dated February 28, 1905.

Application filed April 26, 1904. Serial No. 205,034.

To all whom it may concern:

Be it known that I, JOHN A. STAPLES, a citizen of the United States, residing at Newburgh, in the county of Orange and State of New York, have invented certain new and useful Improvements in Springwork, of which the following is a specification.

This invention relates to wire structures; and the object of the invention is to provide a construction in which a rod or wire may be readily sprung into engagement with opposite sides of a frame or other suitable associated part and which is so organized that when the rod or wire is in position it has a torsional resistance to disengagement from the frame.

The invention consists in the novel construction and organization of parts hereinafter described, and pointed out in the appended claims.

In order to illustrate a use and application, I here show and describe the invention as applied to springwork for bed-bottoms, couches, and other articles of furniture.

In the accompanying drawings, which form a part of this specification, and which illustrate one exemplification of the invention, Figure 1 is a top plan view of a section of springwork made in accordance with my invention, a portion of the figure being broken away and parts being omitted in order to facilitate the illustration of the invention. Fig. 2 is a section on the line 2 2 of Fig. 1. Fig. 3 is a side elevation, on an enlarged scale, of one of the spring-supports. Fig. 4 is a detail plan view showing one end of the support in engagement with the frame. Fig. 5 is a section on the line 5 5 of Fig. 4. Fig. 6 is a detail plan view showing the position of the hook in attaching the support to the frame, and Fig. 7 is a sectional view on the line 7 7 of Fig. 6.

In the class of springwork illustrated the frame 10 is usually composed of a border-wire and is of a size and shape corresponding to the completed article of furniture. In springing up the frame or mounting the springs 11 thereon the springs 11 are carried or sustained by supports 12, which are preferably in the form of longitudinally and transversely dis-

posed wires connected or attached at their ends to the frame, these supports being at such distance apart as is suitable or necessary for the character of the structure being made. The springs 11 are usually arranged in rows or banks and attached or secured to the supports in any suitable manner, as by providing the supports with bends or corrugations adapted to receive the lower ends of the springs and whereby the springs may be seated and sustained at the crossing-points of the supports by interweaving their lower coils with the wires as shown and in a manner now well understood in the art. The tops of the springs are then connected and braced (not shown) in any preferred manner to complete the structure. In the present exemplification of my invention the frame is in the form of a border-wire and the spring-supports are in the form of wires. The support at each end is provided with an integral grip consisting of a rebent end, which in the present embodiment of the invention takes the form of an angular or laterally inclining hook 13, providing a seat for the border-wire. The end 14 of the hook or coil when the parts are assembled extends upwardly within or back of the border-wire far enough to form, preferably, a substantially complete convolution or to a point above the center of the associated border-wire, and this end terminates a distance from the support greater than the thickness of the border-wire, as clearly shown in Fig. 4. The hooks or coils at the opposite ends of each support are inclined or bent reversely to each other and extend laterally in opposite directions or upon opposite sides of the support, as clearly shown in Figs. 1 and 3.

In assembling or setting up the springwork the spring-support is turned from the normal position of Fig. 3, so that the hook at one end occupies a position similar to that shown in Figs. 6 and 7, when the said hook may be slipped over the border-wire at one side or end of the structure, the border-wire seating itself in the hook, as seen in dotted lines in said figures. The support is then partially rotated in such direction as to cause the end 14 of the coil or hook to move up back of the

- border-wire and into the position shown in Figs. 4 and 5. The hook at the opposite end of the support is then twisted or rotated in the same direction given the support to engage the first hook, as in the direction of the arrow, Fig. 6, by any suitable means, as by a pair of pliers, as shown in dotted lines in Fig. 6. This rotation of the free hook is resisted by the support, owing to the opposite 10 attached end, and results in putting the support under tension or torsion. The free hook is rotated far enough to bring its end into a substantially horizontal position below the line of the border-wire, as shown in Fig. 7, and 15 the adjacent stretch of the border-wire having been moved inwardly far enough to clear the end of the hook it is permitted to slip into the seat of such hook, as shown in dotted lines in Figs. 6 and 7. When this hook is released, 20 owing to the torsion of the support the end of the hook springs up into the position shown in Figs. 4 and 5. It is obvious that the parts can become disengaged only by twisting or rotating the ends of the wire or 25 rod, and as such movement is opposed by the torsional resistance of the material of the rod or wire it will require a positive and considerable application of force to effect this movement. By reason of this construction 30 the rod or wire is readily assembled on the parallel associated parts and is securely held against accidental disengagement therefrom. The supports having been assembled with the border-wire the springs are then interwoven 35 at their lower reduced ends with the supports at the intersection or crossing-points of the latter, and the structure may then be completed by connecting up and bracing the tops of the springs in the usual or any preferred manner. 40 As thus constructed, when the spring-support is in assembled position outward movement of the border-wire is prevented by the rear side of the hook, while inward movement is resisted by the end 14 of the 45 hook or coil, which extends upward far enough to prevent the border-wire from riding up out of the seat of the hook even under great pressure. The parts may be readily attached by unskilled workmen, obviating 50 the necessity of using solder, or bending the ends about the frame, or of employing independent or separate clips or connections, and may be manufactured in suitable sizes and shipped separately or in knockdown form to 55 furniture and upholstery factories or jobbers unprovided with facilities for making the metal-work.
- In some instances it may be desirable to have the connecting rod or wire under torsion when 60 in its normal position in engagement with the associated parallel wires at its opposite ends in order to more securely lock or grip the parts together. In such organization the frictional engagement of the connecting rod 65 or wire with the associated parts is increased,

whereby not only is the accidental disengagement of this wire more surely prevented, but its movement or displacement longitudinally of or along its associated wires or frame is prevented. This feature is accomplished by 70 the laterally-inclined hooks at the ends of the connecting-wire being arrested by contact with the under surface of the associated wires or frame before reaching the initial position from which they were rotated or twisted for 75 the purpose of engaging therewith. The hooks at the opposite ends of the support are therefore under constant torsion due to the distortion of the hooks from their position before the support is assembled with the border-wire. Owing to this constant torsion of the support, the hooks grip the border-wire, and as this torsion must be increased in order to disengage the hooks from the border-wire, 80 and as the ends of the hooks extend back of the border-wire, as shown in Fig. 3, accidental displacement and disengagement of the parts are impossible. While I prefer a form in which there shall normally be torsion in the support when both ends are engaged, in order 85 the more securely to lock or grip the parts together, it is obvious that, as described, the parts may be so related as to provide for this torsional strain or resistance occurring only when the supports tend to move out of their 90 normal positions. In other words, the supports may be under torsion only when twisting their ends in assembling or disassembling them.

It is obvious that various changes and modifications in the construction are within the scope of my invention. For example, the frame may be of any suitable material and shape or form, and the supports themselves may be in any other suitable form or of any 100 other suitable material, while the springs obviously may be connected thereto in any suitable manner.

The supports preferably are made of wire and with a hook at each end; but any suitable 110 form of support with connections for attachment to the adjacent frame may be employed; also, one end may be provided with one form of connection and the other with any other suitable form.

As before stated, I have shown and described my invention as applied to and used in springwork for furniture in order to disclose a suitable use therefor; but it is obvious that the interlocking connecting and associated wires may be utilized in other lines of industry, such as in making screens, fences, and many other wire structures.

The invention contemplates a knockdown wire structure in which the parts may be 125 readily snapped into place and will hold by the torsional resistance of the wire.

Having described my invention, I claim—

1. In a wire structure, the combination with a pair of parallel wires, of a connecting-wire 130

having oppositely-directed hooks at its ends engaging the parallel wires and one of which hooks is adapted to be sprung into engagement with its associated parallel wire against the torsion of the connecting-wire.

2. In a wire structure, the combination with a pair of parallel wires, of a connecting-wire engaging the parallel wires at its ends and held from disengagement therefrom by the torsional resistance of the connecting-wire.

3. In a wire structure, the combination with a pair of parallel wires, of a connecting-wire engaging the parallel wires at its ends and under the torsion of its intermediate portion.

4. In a device of the class described, the combination with a frame, of a connecting-wire having end grips engaging the frame at opposite points and held against displacement by the torsional resistance of the connecting-wire.

5. In a device of the class described, the combination with a frame, of a connecting-wire having hooks receiving the frame at opposite points and held from displacement therewith by the torsion of the connecting-wire.

6. In a device of the class described, the combination with a frame, of a connecting-wire having reversely-arranged hooks receiving the frame at opposite points and held from displacement therewith by the torsion of the connecting-wire.

7. In a device of the class described, the combination with a frame, of a spring-support having reversely-arranged hooks receiving the frame at opposite points and held in engagement therewith by the torsion of the support, the end of each hook extending back of the border-wire.

8. In a device of the class described, the combination with a frame, of a spring-support having reversely-arranged hooks receiving the frame at opposite points and held in engagement therewith by the torsion of the support, the end of each hook extending back of the border-wire.

9. In a device of the class described, the combination with a border-wire, of spring-supports having grips receiving the border-wire and held in engagement therewith by the torsion of the supports, and springs carried by the supports.

least as great as the thickness of the frame-wire.

10. In a device of the class described, the combination with a border-wire, of spring-supports having hooks receiving the border-wire at opposite points and held in engagement therewith by the torsion of the supports, and springs carried by the supports.

11. In a device of the class described, the combination with a border-wire, of longitudinal and transverse spring-supports having inwardly-extending hooks receiving the border-wire at opposite points, the ends of the hooks being inclined laterally in opposite directions, and springs carried by the supports at the crossing-points of the latter.

12. In a device of the class described, the combination with a border-wire, of longitudinal and transverse corrugated spring-supports having hooks receiving the border-wire and being held in torsional engagement therewith, the ends of the hooks of each support being bent laterally in opposite directions and extending behind the border-wire, and springs carried by and interwoven with the supports at the crossing-points of the latter.

13. In a device of the class described, the combination with a border-wire, of a connecting-wire having end hooks engaging the border-wire at opposite points and acting in opposition to each other to prevent disengagement of the connecting-wire from the border-wire.

In testimony whereof I affix my signature in presence of two witnesses.

JOHN A. STAPLES.
